CLEANABLE SIEVE

Roy Neher, Clarence Center, N. Y., assignor to
 National Gypsum Company, Buffalo, N. Y., a
 corporation of Delaware

Application September 11, 1931, Serial No. 562,278

11 Claims. (Cl. 209—379)

This invention relates to a sieve, i. e., a screen or foraminous plate for holding back or screening out relatively coarse particles of material, and more particularly to a sieve for use in the bottom 5 of a wet gypsum-aggregate mixer whereby to prevent the extrusion of any excessively large and non-uniformly mixed lumps from said mixer. The principal object of the invention is to provide a sieve which may be conveniently cleaned 10 or cleared out whenever the same becomes excessively clogged up, without the necessity of stopping the entire machine for this periodic cleaning process. Numerous other collateral objects of the invention are disclosed in detail in 15 the herein patent specification wherein:

In the accompanying drawing:

Fig. 1 is a fragmentary top plan view, with the cover removed, of a gypsum-aggregate mixer with my improved cleanable sieve arranged in the bottom thereof.

Fig. 2 is a vertical transverse section thereof taken on line 2—2, Fig. 1.

Fig. 3 is an enlarged, fragmentary section thereof taken on line 3—3, Fig. 1, but with the imperforate plate in its closed position.

Similar characters of reference indicate like parts in the several figures of the drawing.

The present invention is illustrated as used in combination with and as a part of a toothed ball-mill mixer employed for mixing gypsum with aggregate in a moist condition. A typical form of such a mixer is illustrated, the same comprising a casing 10 having vertically cylindrical side walls 11, an approximately flat bottom or floor 12, a cover 13, a vertical, coaxial agitator shaft 14, and a hollow or tubular scraper shaft 15. The lower end of said agitator shaft 14 is suitably journaled in the mixer floor 12 by means of a vertical thrust ball bearing 16 and a radial ball bearing 17. The upper end of said agitator shaft is connected to and driven by any suitable source of power, while to the lower end (above the radial ball bearing 17) is secured, by a key 18, an agitator wheel 20. The periphery of this agitator wheel is serrated 25 to provide a plurality of agitator teeth 21 which are circumferentially uniformly spaced around the periphery of said agitator wheel 20. Each of these agitator teeth 21 is bevelled at 22 and is curvilinear or arcuate in shape and terminates 30 abruptly at its rear end in a square-shouldered, radial indenture 23, at the innermost end of which is located the leading end of the next successive curvilinear agitator tooth 21.

A plurality of mixing spheres or balls 24 are disposed around the inner periphery of the cylindri-

cal side wall 11 of the mixer, these balls being caused to roll around the inner periphery of the stationary cylindrical side wall 11 and at the same time caused to jump up and down by means of the rotation of said agitator wheel 20 and its peripheral, curvilinear teeth 21. A ball-race wear plate 25 is customarily sunk or imbedded in the inner periphery of the cylindrical side wall 11 of the mixer casing 10 so as to enable the same to be replaced, without replacing the entire side 10 wall 11, when the mixer has been in use a considerable period and has become excessively worn down.

Such a mixer is preferably and usually also provided with a scraper hub 26 which is secured 15 (by a press fit) to and is driven by the tubular scraper shaft 15, the speed of the latter being different from the rotative speed of the agitator shaft 14. Secured to said scraper hub 26 by machine screws 27 or otherwise is an upper or 20 cover scraper blade 28, to the outer end of which is fastened, by rivets 30, a vertical or wall scraper 31. Also secured to said scraper hub 26, by screws 270 or otherwise, is a lower scraper blade 32, the lower edge of which slidably engages with 25 and thereby scrapes off the upper surface of the agitator wheel 20. The vertical load thrust or weight of all of these various scraper blades, together with the scraper hub 26 and tubular scraper shaft 15 is borne by a suitable scraper, 30 thrust-bearing 33, while the lateral (horizontal) thrust is borne by a pair of anti-friction bushings 34.

It is to be understood that, although this toothed ball-mill mixer has been described in detail, it forms no organic part of the present invention and has only been thus described so as to make the present disclosure entirely intelligible. The essence of the herein invention is concerned only with the sieves which are located 40 at the bottom of said mixer and are constructed as follows:

At the discharge side of the mixer (lower part of Fig. 1) the floor or bottom plate 12 is arcuately cut away at three points 35 and into each of the 45 cut-away portions is secured, by machine screws 36 or otherwise, a flanged, semi-circular, sieve collar 37. Projecting coaxially upwardly from the outer central part of each sieve collar is a post or vertical pivot 38, secured in place by a set 50 screw 40 or otherwise. Rotatably mounted on each of said pivots 38 is a pair of plates, namely: a sieve plate 41 and an imperforate plate 42, both of said plates being disposed horizontally and having their adjacent faces in close juxtaposi- 55

tion, the imperforate plate 42 being illustrated as being uppermost. Each sieve plate 41 is provided with a plurality of arcuate slots or semi-circular sieve openings 43 which are concentric with respect to the companion pivot 38 and are radially equally spaced from each other. Press fitted or otherwise secured to the bottom face of each imperforate plate 42 are a plurality of clearing prongs 44 the lower ends of which are bevelled at 45. Each of said clearing prongs projects downwardly into and is snugly received within a companion arcuate opening 43 of its companion sieve plate 41. Each sieve plate is provided with a radial, outwardly projecting, operating handle 46, while each imperforate plate 42 is similarly provided with an operating handle 47. The annular (semi-circular) edge of each imperforate plate 42 is provided with a single-bevelled periphery 48 which is received in and is guided by a single bevelled guideway 50 formed coaxially with respect to the pivot 38, in its companion sieve collar 37. The annular (semi-circular) edge of each sieve plate 41, on the other hand, is provided with a double-bevelled periphery 51 which is received in and is guided by a double-bevelled guideway 52 formed (also coaxially with the pivot 38) in its companion sieve collar 37.

Operation

30 The gypsum and viscous aggregate (or other materials to be intimately ground together and mixed) are fed into the top of the cylindrical casing 10 and are thoroughly mixed therein by the combined rolling and up and down jostling action of the mixing balls 24, the same being caused to rotate by reason of the rotation of the agitator wheel 20 driven by the agitator shaft 14, and being caused to be jumped up and down by reason of the agitator teeth 21 of said agitator wheel. The material being mixed is prevented from permanently sticking to the inner parts of the mixer by reason of the various scraper blades 28, 31 and 32 driven by the tubular scraper shaft 16.

45 Normally, while the mixer is in operation, the mixed material is squeezed by gravity and by the action of the balls 24 down through the bore of the three sieve collars 37 and through the arcuate sieve openings 43 of the sieve plate 41. These 50 sieve plates hold back or retain the excessively large lumps of material and the insufficiently mixed accretions, thereby ensuring that only sufficiently fine and masticated or mixed material will be discharged from the mixer.

55 It occasionally happens, however, that the sieve openings 43 of said sieve plates become clogged up and it has heretofore been the practice to shut down the entire machine in order to effect a cleaning or clearing out of said sieve plate 60 openings. In the present invention, the operator does not need to disturb the operation of the machine. Instead he merely grasps the operating handle 46 of the more or less clogged-up sieve plate and rotates the same a half revolution in 65 a clockwise direction. This action causes the clearing prongs 45 of the companion imperforate plate 42 to traverse the arcuate openings 43 of the offending sieve plate 41 and to push out therefrom any clogged up material. The bevelled 70 end 45 of each clearing prong 45 permits the latter to only touch the one (outer) side of its sieve opening 43 with its entire length, the other (inner) side of said sieve opening being only partly engaged by its companion cleaning prong 75 45. This construction prevents any wedging or

packing action, and thereby renders the clearing operation very easy, and also causes the packed or clogged material to be entirely sheared off from the sides of the sieve openings 43 without any at least pronounced tendency to pack the 5 material down against the said sides of said sieve openings.

During the operation of the mixer it is occasionally desirable to either partially or wholly cut off the flow of mixed material through any one 10 or more of the sieve plates 41. In the present invention, such a result is obtained by merely grasping the operating handle 47 of the desired imperforate plate 42 and turning the same in a counter-clockwise direction as far as may be 15 desired, thus cutting off any desired amount of the flow through its companion sieve plate 41.

It should be noticed that each imperforate plate 42 is located above its companion sieve plate 41, so that the portions of the arcuate sieve 20 openings 43 which are not in use are covered, as otherwise they would be likely to become packed hard with the material being macerated in the mixer and would require being cleaned out before being fit for service when the imperforate plate 25 is subsequently to be more or less opened up. The effect of the bevelled peripheries of each sieve plate 41 and imperforate plate 42 are also of importance. The double-bevelled periphery 51 of each sieve plate 41, engaging as it does with the 30 double-bevelled guideway 52 of the sieve collar 37, restrains said sieve plate against upward as well as downward displacement, and thus relieves the vertical strains which would otherwise be imposed on the pivot 38 and at the same time 35 definitely restrains said sieve plate against any accidental upward displacement and against excessive upward pressure against the imperforate plate 42. The latter, having its semi-circular edge formed to provide the single bevelled periphery 48 (which is received by the single-bevelled guideway 50) ensures that the lower face of said imperforate plate is always in close contact with the upper face of the sieve plate 41, this action being ensured by the fact that inevitably, a certain amount of to-be-mixed material is sure to be packed in between said single bevelled periphery 48 and its companion single bevelled guideway 50.

45 I claim as my invention:

1. A sieve adapted to screen material and comprising a pivoted arcuate plate provided with a concentric, arcuate opening through which the entire mass of said material is adapted to flow; a clearing prong normally located at one end of said opening and projecting thereinto; and means whereby said plate may be swung about its pivot in a plane perpendicular to said clearing prong and thereby to clear said opening.

2. A sieve adapted to screen material and comprising a normally stationary pivoted arcuate plate provided with a concentric, arcuate opening through which the entire mass of said material is adapted to flow; a clearing prong normally located at one end of said opening and projecting thereinto; and means whereby said plate may be swung about its pivot in a plane perpendicular to said clearing prong and thereby to clear said opening.

3. A sieve adapted to screen material and comprising a pivot; a sieve plate having an arcuate opening through which the entire mass of said material is adapted to flow arranged concentrically with respect to said pivot; and an imperforate plate adapted to swing about said pivot and 75

provided with a clearing prong arranged parallel with the axis of said sieve plate and projecting into the opening of said sieve plate.

4. A sieve adapted to screen material and comprising a pivot; a sieve plate mounted on and adapted to be moved about said pivot and having a concentrically arranged opening through which the entire mass of said material is adapted to flow; and an imperforate plate also arranged on 10 said pivot and also adapted to be moved about said pivot and having a clearing prong arranged parallel with the axis of said sieve plate and projecting into said opening.

5. A sieve adapted to screen material and comprising a pivot; a sieve plate having an arcuate opening through which the entire mass of said material is adapted to flow and mounted on said pivot and provided with a handle whereby it may be manually swung about said pivot; an 20 imperforate plate also mounted on said pivot and also provided with a handle whereby it may be manually swung about said pivot; and a clearing prong arranged parallel with the axis of said sieve plate and secured to said imperforate plate and 25 projecting into the arcuate opening of said sieve plate.

6. A sieve comprising a sieve plate adapted to screen material by restraining the flow therethrough of excessively large particles and having 30 an opening through which the entire mass of said material is adapted to flow; an imperforate plate arranged against one flat face of said sieve plate and having a bevelled periphery; a casing having a bevelled guideway which receives the peripheral edge of said sieve plate; and a clearing prong secured to said imperforate plate and projecting into the opening of said sieve plate.

7. A sieve adapted to screen material and arranged in a casing having a pair of oppositely bevelled guideways; a sieve plate having an opening through which the entire mass of said material is adapted to flow and having a bevelled edge arranged to engage with one of the bevelled guideways of said casing; and an imperforate 45 plate also having a bevelled edge and arranged to engage with the other bevelled guideway of

said casing; and a clearing prong secured to said imperforate plate and projecting into the opening of said sieve plate.

8. In a sieve for a gypsum-aggregate mixer and adapted to restrain the flow therethrough of the 5 coarse and improperly mixed lumps, comprising a casing having a single annular bevelled guideway and a double annular bevelled guideway; a pivot arranged in said casing; a sieve plate having a double bevelled periphery and arranged to 10 engage with said double bevelled guideway and having an arcuate opening through which the entire mass of said material is adapted to flow; an imperforate plate having a single bevelled periphery and arranged to engage with said 15 double bevelled guideway; and a clearing prong bevelled at its outer end and secured to said imperforate plate and projecting into the arcuate opening of said sieve plate.

9. A cleanable sieve comprising: a frame; a 20 sieve plate having an elongated opening; an imperforate plate adapted to have its leading edge moved horizontally over the upper surface of said sieve plate; and a clearance prong projecting downwardly from the lower face of said imperforate 25 plate back of its leading edge and received within said opening.

10. A cleanable sieve comprising: a frame; a sieve plate having an elongated opening; an imperforate plate adapted to have its leading edge 30 moved horizontally over and in intimate shearing contact with the upper surface of said sieve plate; and a clearance prong projecting downwardly from the lower face of said imperforate plate back of its leading edge and received within 35 said opening.

11. A cleanable sieve comprising: a frame; a sieve plate having an elongated opening; an imperforate plate having a leading edge and adapted to cover the entire surface of said sieve plate 40 and to be moved over the upper surface thereof; and a clearance prong located just back of the leading edge of said imperforate plate and projecting downwardly from the lower face thereof and received within said opening.

45
ROY NEHER.
